UNITED STATES PATENT OFFICE.

EMIL TYDEN, OF HASTINGS, MICHIGAN.

CAR-SEAL LOCK.

1,080,186.

Specification of Letters Patent.

Patented Dec. 2, 1913.

Application filed March 15, 1913. Serial No. 754,455.

To all whom it may concern:

Be it known that I, EMIL TYDEN, a citizen of the United States, residing at Hastings, in the county of Barry and State of Michigan, have invented new and useful Improvements in Car-Seal Locks, of which the following is a specification, reference being had to the accompanying drawings, forming a part thereof.

10 The purpose of this invention is to provide an improved seal lock for railway cars, designed to be sealed in such manner that after the car is unlocked and opened it cannot be completely re-sealed until the car has 15 been moved on the track or disturbed to an extent equivalent to such movement, thus preventing the unauthorized entry of the car and re-sealing it with an imitation seal while the car remains entirely at rest on the 20 track.

It consists in the elements and features of construction shown and described, as indicated in the claims.

In the drawings:—Figure 1 is a front elevation of a portion of a car body and door having a lock embodying the present invention, showing the same fully sealed. Fig. 2 is an elevation of the lock mechanism with the front cap of the lock removed. Fig. 3 is a horizontal section at the line, 3—3, on Fig. 2, with the cap in position. Fig. 4 is a section at the line, 4—4, on Fig. 3. Fig. 5 is a detail front elevation showing the lock partly sealed, having the main locking bolt 35 sealed with a certain form of seal. Fig. 6 is a detail front elevation with a portion of the case broken away to disclose part of the interior structure, with the parts in the condition and positions which would be occupied if the car had been unlocked and re-sealed as far as possible without moving the car. Fig. 7 is a view similar to Fig. 2 showing a modified device embodying a portion of this invention. Fig. 7^a is a section at the 45 line, 7^a—7^a, on Fig. 7. Fig. 8 is a plan view of a suitable form of seal.

In the drawings, the lock case, 1, is shown secured upon a car body, 2, in the usual position for securing a sliding door by 50 means of a hasp, 3, on the door, engaging the staple, 4, of the lock, and there secured by the main bolt, 5, of the lock, said main bolt being mounted for vertical sliding in the casing, 1. The main bolt is shown provided with a seal-receiving aperture, 5^a, through which any form of flat seal may

be inserted and secured in any known manner. In the drawings a particular form of seal is shown which will be hereinafter described, being adapted to certain preferred modes of use of the lock herein shown. The seal aperture, 5^a, is in the end portion of the bolt below the staple, 4. In the casing, 1, there is mounted for sliding parallel with the main bolt, 5, an auxiliary bolt or tumbler, 7, which has also a seal-receiving aperture, 7^a, in the lower end portion of said auxiliary bolt, said lower end portion being adapted to protrude from the casing at fully locked and sealed position so as to expose 60 said seal aperture, 7^a, for the insertion of a seal therethrough; and this auxiliary bolt may be made to operate for locking, as illustrated, by extending the hasp, 3, over an auxiliary staple, 4^a, for engagement of the 65 hasp and the auxiliary bolt. The main bolt, 5, has an arm, 5^c, extending off from said main bolt across the auxiliary bolt, 7, and between shoulders, 7^b and 7^d, on said auxiliary bolt which are so located that at the 70 unlocked position of the main bolt, 5, said arm, 5^c, holds the auxiliary bolt, 7, out of seal-receiving position. The distance between the shoulders, 7^b and 7^d, is such that the main bolt, 5, may be returned to locking 75 position without restoring the position of the auxiliary bolt, 7, said arm, 5^c, merely moving between the shoulders, 7^b and 7^d, in its locking movement. Within the casing, 80 there is pivotally supported for swinging 85 back and forth lengthwise of the car,—that is, parallel to the plane of the back plate of the casing,—a pendulous member, 8. This member may be pivoted upon the auxiliary bolt, 7, but this is not essential though the 90 further details of construction shown are adapted to this mode of pivoting said pendulous member.

A catch device is provided in the casing for automatically engaging the auxiliary bolt, 7, with the casing at its withdrawn position,—that is, at the position at which the seal aperture, 7^a, is within the casing and inaccessible for sealing. As a matter of convenience, this catch device may be 100 pivoted upon the auxiliary bolt, 7, and engage an abutment on the casing, as shown in the drawings, said catch device being a hook, 9, having a catch nose, 9^a, with an oblique face, which, in the upward or with- 105 drawing movement of the auxiliary bolt, encounters a fixed stud, 10, on the casing, 110

and being deflected past it falls back into engagement with it at the most withdrawn position of the auxiliary bolt. As illustrated, this engaging action of the catch hook is effected by gravity caused by the fact that the catch hook has an arm, 9^b, extending off from its pivoted end and overhanging an arm, 8^b, which extends off from the pivoted end of the pendulous member, 8, and which is stopped by said arm, 8^b, at a position at which the oblique face of the nose, 9^a, will encounter the stud, 10, in the withdrawing movement of the auxiliary bolt, and whose weight tends to swing the catch hook back over said stud after it has been deflected to pass it. The reason for making the catch hook a separate piece from the member, 8, is that said member, 8, by this means acquires some impetus in its swing before the frictional resistance to disengagement of the hook from the stud is encountered.

In using this lock, it is designed that the shipper having loaded the car will close the door and lock it by dropping the main bolt, 5, into locked position and will then secure that main bolt by a seal of any suitable form, as, for example, the seal, 12, inserted through the seal aperture, 5^a, and secured by bending it at the line, 12^a, to prevent its withdrawal, (the seal being of such character that it cannot be straightened back into position for withdrawal without breaking at the line, 12^a). When the car which is presumed to have been loaded on the shipper's track is picked up by the train, the first movement which it receives in coupling to the train or moving it from the loading track, will cause the pendulous member, 8, to swing, and by means of the arm, 8^b, encountering the arm, 9^b, of the catch hook to disengage the catch hook from the stud, 10, whereupon the auxiliary bolt, 7, will drop and expose the seal aperture, 7^a, outside the casing. The train conductor, or other representative of the carrier, will now apply a seal to said auxiliary bolt, 7, inserting it through the seal aperture, 7^a. For this purpose, the seal, 12, is shown double, having an easy breaking line at 12^b, so that the conductor may detach the member at the left of said breaking line, and use it as a second seal to secure the auxiliary bolt, 7, inserting its reduced end portion through the seal aperture, 7^a, and bending it at the weakened line, 12^c. The use of the double seal shown is not essential. Any seal may be used by the shipper, and any other seal may be used by the carrier. The duplex seal shown has, however, certain advantages, as will hereinafter appear. If at any point during transportation, when the car is standing still on the track, an unauthorized person breaks the seals and unlocks the car, the unlocking movement of the

main bolt, 5, will cause the arm, 5^c, to carry up the auxiliary bolt, 7, withdrawing the seal aperture, 7^a, into the casing where it will be inaccessible, and the auxiliary bolt will be automatically engaged and retained at such withdrawn position by the catch hook, 9, engaging the stud, 10. The intruder may close and lock the car,—that is, may move the bolt, 5, to locking position,—and may apply an imitation or duplicate seal to said locking bolt, and to that extent restore the original appearance, for the purpose of preventing detection of the unauthorized intrusion; but he cannot re-seal the auxiliary bolt, because its seal aperture is at an inaccessible position in the casing and will so remain until some movement of the car causes the pendulous member, 8, to release the catch hook and to permit the auxiliary bolt to protrude to seal-receiving end. A thief, taking opportunity of the halting of the car in transit to break in and rob it, would be obliged to remain in the vicinity of the car until it was moved on the track in order to re-seal the auxiliary bolt, as would be necessary to prevent the discovery at the next inspection of the train of the fact that the car had been tampered with; and the provision of this auxiliary bolt automatically withheld from sealing position until the car is moved, thus practically insures a prompt detection of felonious intrusion into a car thus sealed.

In order that the pendulous member, 8, may not be kept constantly swinging on its pivot while the car is traveling, which would tend to cause unnecessary wear at the pivot, it is formed with rib, 8^c, having a tapered lower terminal, 8^d, which in the descending movement of the auxiliary bolt enters a tapered notch, 5^d, in the arm, 5^c, which holds the pendulous member fixed against swinging at all times when the auxiliary bolt is at seal-receiving position, or the main bolt, 5, is at unlocked position. From this it results that the pendulous member can swing but once for each instance of unlocking the car; for it is only when the car has been unlocked by lifting the main bolt, 5, and then has been locked by dropping that bolt, leaving the auxiliary bolt hooked up at withdrawn position, that the pendulous member can swing; and as soon as it swings once, the auxiliary bolt is released and drops into the position at which the pendulous member is locked against swinging, where it will remain until the car is again unlocked and re-locked.

The duplex or double seal shown in the drawings is especially adapted for use with the lock of the character shown, by reason of the advantages afforded by certain features of that seal which will now be pointed out. It is designed that these seals shall be furnished in bunches on a retaining ring

for which an aperture, 12^a, is made in the stub member, 12^y, of the seal. The seals are identified by a serial number marked upon the stub and also upon the left-hand member of the seal which is applied by the representative of the carrier as hereinafter explained. It is designed that the shipper shall break off the seal from the stub at the perforated line provided to facilitate such breaking and insert the right hand reduced end of the right-hand member through the seal, bending the protruding portion at a line crossing the aperture, 12^a, to fold the end portion back against the bolt. This end portion may be provided with characters to denote either the shipper or the carrier, as preferred. The left-hand member of the seal has the serial number corresponding with the number on the stub retained by the shipper, but said number on said left-hand member is placed upon the rear or inner surface of the seal so as to be not legibly accessible after the seal with the two members not yet broken apart has been applied by the shipper, as above described. The train conductor being obliged to record the seal number must fold back the left-hand member of the seal in order to read the number, and the seal is so weakened at the breaking line, 12^b, that it will break upon being thus folded back, and this construction tends to prevent the conductor from omitting to use the left-hand member of the seal for sealing the auxiliary bolt, 7. It will be observed that the number remains on the left-hand member of the seal when it is applied in sealing said auxiliary bolt, and serves as identification of the seal in subsequent inspections.

It will be understood that the seal illustrated is adapted to perform the function of a seal by virtue of the fact that being weakened at the line for which it is folded for retaining it in the bolt, it will break at this line upon being straightened back, as will be necessary in order to withdraw it from the bolt, so that any attempt to remove the seal will destroy it as a seal,—that is, will prevent it from being re-applied so as to appear as if it had not been disturbed.

I have termed the part, 7, a "bolt" because it has a bolt-like movement, and by its protrusion from the casing is adapted to be utilized directly in locking if desired; but by virtue of its function, as described, in connection with the main bolt, it may properly be considered as a tumbler or bolt-securing member; and I do not wish to be understood by the use of the term "bolt" applied to this part, 7, as limiting myself to a device having independent locking capacity; for it will be evident upon consideration of the structure shown and the mode of operation described that an important part of the result obtained is entirely inde-

pendent of the fact that the auxiliary bolt actually effects locking, it being sufficient that it is adapted to receive a seal and cannot be withdrawn into the case until the seal is removed. On the other hand, it will be observed that when the auxiliary bolt is an actual locking bolt, there is no necessity for a connection from the main bolt to the auxiliary bolt by which the latter is withdrawn when the former is moved to unlocked position, though such connection may still be retained without disadvantage, but in its absence, or if it should be broken off, the person opening the car will disengage both bolts by hand, withdrawing the main bolt in the usual manner, and pushing up the auxiliary bolt with one finger until it becomes engaged with the catch which will retain it out of locking position. It will be observed also that an important part of the purpose of the device is independent of the main bolt, when the auxiliary bolt, is an actual locking bolt; because when the car is loaded by the employees of the carrier and is immediately ready for sealing by the carrier, or when, for any other reason there is no interval between the loading and the time when the car is moved, during which the protection of sealing is required, only the carrier's seal may be applied, and that to the auxiliary bolt. And in such case, if the car is afterward entered, the seal being broken for that purpose, it cannot be re-sealed until the car has been moved on the track, and thus a principal purpose of the device will be effected without bringing the main bolt into operation, or even without the presence of more than the one bolt, and that one corresponding to the bolt termed the auxiliary bolt in the construction illustrated.

In Fig. 7 there is illustrated a modification which comprises one of the main features of the invention as embodied in the preceding figures, namely, the provision of a seal-receiving member which, after once unlocking, cannot be returned to seal-receiving position until the car has been moved or disturbed on the track. In this form the main locking bolt operates substantially as in the form previously described, but the auxiliary device for receiving the second seal is a lever pivoted in the casing having an up-standing arm, 20, weighted at its upper end, and which has a downwardly-extending projection, 22, for thrusting out of the case to receive the seal. When this seal-receiving end, 22, is withdrawn within the casing the center of gravity of the lever is carried sufficiently past the pivot axis to counter-balance the projection, 22, and cause the device to be held normally by gravity at that position,—that is, with the seal-receiving terminal withdrawn into the case. When the main locking bolt is lifted in the

unlocking movement, it encounters the lever, 20, at any suitable point for rocking the up-standing arm, 20, past the fulcrum in the direction for withdrawing the seal-receiving end, 22, into the case where it is held with the seal aperture inaccessible until some movement of the car on the track causes the weighted upper end of the up-standing arm, 20, to receive an impetus which carries it back past the fulcrum, whereupon, being over-balanced at the side toward which it thus moves, the movement will be continued and the seal-receiving terminal, 22, will be thrust out into accessible position outside of the case so that a seal may be applied to it; but if the car has been unauthorizedly opened, or if the main locking bolt has been unauthorizedly withdrawn from unlocking position, the seal in the protruding end, 22, being broken and removed for that purpose, the lock cannot be re-sealed until the car has been afterward moved on the track. In this form it is convenient to effect the engagement of the auxiliary seal-receiving device by the main locking bolt in the unlocking movement by having the arm of the main locking bolt which actuates the said auxiliary member make it encounter with said member against the up-standing arm, 20, by means of a forwardly-projecting finger, 5d.

I claim:—

1. In a car seal lock, in combination with a casing, a principal locking bolt mounted therein for locking and unlocking movement; an auxiliary bolt adapted for sealing mounted in the casing for movement into and out of sealing position; connections between the two bolts by which the unlocking movement of the principal bolt withdraws the auxiliary bolt from sealing position; a catch adapted for engagement to retain the auxiliary bolt at such withdrawn position; a pivoted member adapted to be swung on its pivot by movement of the car, and means by which, in such swinging movement, it releases the catch.

2. In a car seal lock, in combination with a casing, a principal locking bolt mounted therein for locking and unlocking movement; an auxiliary bolt adapted for sealing; mounted in the casing for movement into and out of sealing position; connections between the two bolts by which the unlocking movement of the principal bolt withdraws the auxiliary bolt from sealing position, said connections being constructed with a range of play equal to the movement of the principal bolt from unlocked to locked position, whereby the principal bolt to be moved to locking position without moving the auxiliary bolt; a catch adapted for engagement to retain the auxiliary bolt at withdrawn position; a member mounted in the casing with freedom of movement therein, and adapted

to be moved by the movement of the car, and means by which such movement of such member releases the catch.

3. In a car seal lock, in combination with a casing, a principal locking bolt mounted therein for locking and unlocking movement; an auxiliary bolt adapted for sealing mounted in the casing for movement into and out of sealing position; connections by which the principal bolt withdraws the auxiliary bolt from sealing position when said principal bolt is withdrawn from locking position, said connections being adapted to permit the auxiliary bolt to remain out of sealing position while the principal bolt moves to locking position; a catch adapted to retain the auxiliary bolt out of sealing position; a pivoted member within the casing adapted to be swung on its pivot by movement of the car; means by which in such swinging it releases the catch, and means by which the movement of the auxiliary bolt to sealing position locks said pivoted device against swinging.

4. In a car seal lock, in combination with a casing, a principal locking bolt mounted therein for locking and unlocking movement; an auxiliary bolt adapted for sealing, and mounted in the casing for movement into and out of sealing position, the principal bolt having an arm engaging said auxiliary bolt for moving the latter out of sealing position by the movement of the locking bolt in the opposite direction without moving the auxiliary bolt; a catch mounted on the auxiliary bolt, and means on the casing which the catch engages to retain the auxiliary bolt out of sealing position; a pendulum device pivoted on the auxiliary bolt for being swung on its pivot by movement of the car, and means by which such swinging movement releases the catch.

5. In a car seal lock, in combination with a casing, a principal locking bolt mounted therein for locking and unlocking movement; an auxiliary bolt adapted for sealing, mounted in the casing for movement into and out of sealing position, the principal bolt having an arm which engages the auxiliary bolt for moving the latter out of sealing position when the former is moved out of locking position, the parts being constructed to permit the movement of the locking bolt in the opposite direction without movement of the auxiliary bolt; a catch and an abutment for engagement of the catch, one of said parts mounted on the auxiliary bolt and the other on the casing for retaining the auxiliary bolt out of sealing position; a device pivoted for swinging when the car is moved, and means by which such swinging releases the catch, and means by which said device is locked against swinging at the sealing position of the auxiliary bolt.

6. In a car seal lock, in combination with

a casing, a principal locking bolt mounted therein for locking and unlocking movement; an auxiliary bolt adapted for sealing, mounted in the casing for movement into and out of sealing position, the principal bolt having an arm which engages the auxiliary bolt for moving the latter out of sealing position when the former is moved out of locking position, the parts being constructed to permit the movement of the locking bolt in the opposite direction without movement of the auxiliary bolt; a catch and an abutment for engagement of the catch, one of said parts mounted on the auxiliary bolt and the other on the casing for retaining the auxiliary bolt out of sealing position; a device pivoted for swinging when the car is moved, and means by which such swinging releases the catch, and means by which said device is locked against swinging at the unlocked position of the locking bolt.

7. In a car seal lock, in combination with a casing, a principal locking bolt mounted therein for locking and unlocking movement; an auxiliary bolt adapted for sealing, mounted in the casing for movement into and out of sealing position, the principal bolt having an arm which engages the auxiliary bolt to move the latter out of sealing position when the former is moved out of locking position, the relation of said arm to the auxiliary bolt being adapted for movement of either bolt in the opposite direction without moving the other; a catch and an abutment for engagement of the catch, one of said parts being on the auxiliary bolt and the other pivoted on the casing, in position to be swung by the movement of the car, and means by which such pivoted device in such swinging movement releases the catch, said pivoted device being positioned for overhanging said arm of the principal bolt, and adapted to engage by said arm against swinging when the auxiliary bolt moves to sealing position.

8. In a car seal lock, in combination with a casing, a principal locking bolt mounted therein for locking and unlocking movement; an auxiliary bolt adapted for sealing, mounted in the casing for movement into and out of sealing position, the principal bolt having an arm which engages the auxiliary bolt to move the latter out of sealing position when the former is moved out of locking position, the relation of said arm to the auxiliary bolt being such, that either bolt may move in the opposite direction without moving the other; a catch and an abutment for engagement of the catch, one of said parts being on the auxiliary bolt and the other on the casing, adapted to retain the auxiliary bolt out of sealing position; a device pivoted on the auxiliary bolt adapted to be swung by the movement of the

car, and means by which such pivoted device in such swinging movement releases the catch, said pivoted device being positioned for overhanging said arm of the principal bolt, and adapted to engage by said arm against swinging when the locking bolt moves to unlocked position.

9. In a car seal lock, in combination with a casing, a principal locking bolt mounted therein for locking and unlocking movement adapted to be sealed at the locking position; an auxiliary bolt adapted to be sealed, mounted in the casing for movement into and out of sealing position; inaccessible means in the casing for retaining the auxiliary bolt out of sealing position adapted to be released by movement of the car to permit the auxiliary bolt to move into sealing position when the car is moved, and a duplex seal adapted to be applied and secured to the locking bolt without application to the auxiliary bolt, and to be subsequently applied and secured also to the auxiliary bolt.

10. In a car seal lock, in combination with a casing, a principal locking bolt mounted therein for locking and unlocking movement adapted to be sealed at the locking position; an auxiliary bolt adapted to be sealed and mounted in the casing for movement into and out of sealing position; inaccessible means in the casing for retaining the auxiliary bolt out of sealing position adapted to be released by movement of the car to permit the auxiliary bolt to move into sealing position when the car is moved, and a duplex seal comprising two members and means for identifying said members, respectively; said seal being adapted to have one of its members applied and secured to the main locking bolt, and being provided with a breaking line for detaching the other member after the first member is so applied and secured, the second member being adapted after breaking from the first to be applied and secured to the auxiliary bolt.

11. In a car seal lock, in combination with a casing, a principal locking bolt mounted therein for locking and unlocking movement adapted to be sealed at the locking position; an auxiliary bolt adapted to be sealed and mounted in the casing for movement into and out of sealing position; means for retaining the auxiliary bolt out of sealing position adapted to be released by movement of the car to permit the auxiliary bolt to move into sealing position when the car is moved, and a duplex seal comprising two members and means for identifying said members, respectively; said seal being adapted to have one of its members applied and secured to the main bolt when the auxiliary bolt is out of seal-receiving position, the other member being adapted to be detached from the first member by folding the seal back upon itself, the means of identifying said second mem-

ber being upon the inner surface of said member so as to be not legibly accessible without folding said member for detaching it.

- 5 12. In a car seal lock, in combination with a casing, a main locking bolt mounted therein for locking and unlocking movement; an auxiliary seal-receiving member mounted in the casing and adapted to protrude therefrom for receiving a seal; means associated with said auxiliary member for holding it out of seal-receiving position, said means being adapted to be moved by the movement of the car out of the position at which it 10 thus retains said auxiliary member, and means by which the main locking bolt in its unlocking movement withdraws the auxiliary seal-receiving member from seal-receiving position.
- 15 13. A car seal locking device comprising, in combination with a casing, a seal-receiving member mounted in the casing for movement into and out of sealing position; a locking bolt adapted to be moved at will for locking and unlocking, connections by which the unlocking movement of the locking bolt withdraws the seal-receiving member from seal-receiving position, and means mounted in the casing for holding it out of seal-receiving position, adapted to be released by the movement of the car to permit it to return to seal-receiving position.
- 20 14. A car seal locking device comprising a bolt mounted for locking and unlocking; an auxiliary seal-receiving device and a casing in which it is mounted so as to be adapted to be moved by the operator out of seal-receiving position; connections between the locking bolt and the seal-receiving member 25 by which the latter, at seal-receiving position, prevents the movement of the former from locking position; a catch mounted in the casing for automatically engaging said auxiliary device to retain it out of seal-receiving position, and a device mounted with-

in the casing so as to be moved by movement of the car, adapted in such movement to release the catch.

15. In a car seal lock, in combination with a casing, a main locking bolt mounted there-in for locking and unlocking movement; an auxiliary seal-receiving member mounted in the casing for movement into and out of sealable position; means associated with said auxiliary seal-receiving member for retaining it in unsealable position after it is moved to such position, said means being adapted to be moved by the movement of the car away from position for so retaining the seal-receiving member, and means by which the locking bolt, when moving to unlocked position, moves the seal-receiving member to unsealable position.

16. In a car seal lock, in combination with a casing, a bolt adapted for sealing at its locking position mounted in the casing for movement into and out of sealing position, and inaccessible means in the casing for holding said bolt out of sealing position adapted to be released by the movement of the car to permit the bolt to move to seal receiving position.

17. In a car seal lock, in combination with a casing, a bolt adapted for locking and for sealing at locked position mounted in the casing for movement into and out of its sealing position inaccessible means in the casing for automatically engaging the bolt at its unlocked position for holding it out of sealing position, adapted to be released by the movement of the car to permit said bolt to be moved to seal-receiving position.

In testimony whereof, I have hereunto set my hand, at Chicago, Illinois, this 13th day of March, 1913.

EMIL TYDEN.
